FIG. 1

FIG. 5

INVENTOR

Andrew Christianson
By Archibald Martin,
Attorney.

UNITED STATES PATENT OFFICE.

ANDREW CHRISTIANSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

CAR CONSTRUCTION.

Application filed January 14, 1926. Serial No. 81,193.

My invention relates to car constructions, and particularly to a form of structure especially suitable for car ends and car doors.

One object of my invention is to provide a car end of such form that there is less danger of opening of the joints between the edges of the car ends and the adjacent walls of the car, and wherein the car end is joined more firmly to the adjacent walls than in structures heretofore employed.

Another object of my invention is to provide car end structure wherein improved means are provided for preventing passage of air or moisture past the edges of the car end to the interior of the car.

Another object of my invention is to provide a car end so mounted as to be movable out of closed position, thereby serving as a door for providing access to the interior of the car.

Another object of my invention is to provide a door structure having an improved form of locking mechanism, and one wherein provision is made for effecting a tight closure as between the edges of the door and cooperating door frame structure.

One form which my invention may take is shown in the accompanying drawing, wherein Fig. 1 is an end elevational view of a car with my invention applied thereto; Fig. 2 is a vertical sectional view on the line 2-2 of Fig. 1; Fig. 3 is an enlarged elevational view of the locking mechanism; Fig. 4 is a section on the line 4-4 of Fig. 3, and Fig. 5 is a section on the line 5-5 of Fig. 1, showing the corner structure of the car at the hinge side of the door.

For convenience of description I have shown my invention as applied to a railway car end wherein such end is hingedly mounted to serve as a door to provide access to the interior of the car, but the invention is not limited to car ends nor to car ends that serve also as doors.

The door is composed of panels 11 and 12 riveted together at their adjacent edges and having marginal angles 13, 14, 15 and 16 riveted thereto.

The door is shown as supported against a framework composed of vertical angles 17 and 18 (Figs. 4 and 5) that are secured to the posts 19 and 20, respectively, which form a portion of the side walls of the car. A top frame member is also provided consisting of plates 21 and 22 (Fig. 2) that are connected

to the side wall structures of the car in any suitable manner. A bottom door frame structure consists of a plate 23 that is secured to the floor 24 of the car and the end sill or platform 25.

Four hinges 26 are secured to the door and to an angle iron 27 that extends vertically the full height of the door and is secured to the angle 18. A plate 28 is secured to the angle 14, such plate being provided with an outwardly turned edge that cooperates with the in-turned edge of the bar 27, thereby creating an overlapping structure which tends to prevent access of moisture or entry of air past the edge of the door.

Three latch bars 30 (Figs. 3 and 4) are provided at the right hand edge of the door to hold the same closed. These latch bars are each pivotally mounted upon a pin 31 that is supported in bearings 32 which are fastened to the side wall structure of the car. The bars 30 are held in latched position by means of locking pins 33 that extend through openings in the flanges 34 of keepers 35 that are secured to the face of the car end. The upper ends of the locking pins 33 are bent over at 33^a so that the pin may be turned to the position indicated in dotted lines in Fig. 3, and the end 33^a caused to rest upon a ledge 35^a to thereby hold the locking pin 33 in raised position and permit the latch bar 30 to be swung outward.

The bearing brackets 32 are each connected to the forward end of a spring plate 36 (Fig. 4) by means of rivets 37, the spring plates in turn being riveted to the vertical angles 17 of the side wall. A vertically-extending angle bar 38 is disposed between the spring plate 36 and the bearing bracket 32 with its flange turned inwardly to overlap the outwardly extending flange of a vertically disposed angle 39 that is secured to the door frame angle 13, thereby making a tight joint between the edge of the door and the adjacent side of the car. The angle bars 38 and 39, when overlapped as shown in Fig. 4, serve as stop members for holding the door closed.

A guide member 41 is provided for each latch bar 30, such guide member being rigidly secured to the angles 17 and 13. In order to open the door, the pin 33 is raised to the position shown by dotted lines in Fig. 3, and the latch bar 30 swung outward about its pivot 31 until its cam surface 30^a is

brought into engagement with the guide 41. The guide 41 is rigid and the bar 38 is therefore forced out of the path of the angle 39, by reason of the camming engagement 5 between the surface 30^a and the guide 41 and consequent outward flexing of the spring plate 36. The door can then be moved to fully open position, thus providing unobstructed access to the interior of the car. In 10 closing the door, the rear face of the angle 39 is brought into engagement with either the camming surface 30^a of the latch bar or with the camming surface 32^a of the supporting bracket 32, to force the angle 38 outward and 15 permit the angle 39 to assume the position shown in Fig. 4, at which time the lever 30 can again be locked.

A sealing joint is provided at the top of the car by means of an angle 43 (Fig. 2) that is 20 connected to three hinges 44 (Fig. 1) that are secured to the end plate 21. The outer edge of the angle 43 overlaps the door frame angle 16, as shown more clearly in Fig. 2, and its inner end is turned upwardly between the 25 plates 21 and 22 that extend across the end of the car. The angle 43 is connected to two links 45, so that when it is desired to open the door, pins 46 by which the links are supported from the bracket 46^a are removed 30 from the brackets and the links lifted until their openings 47 are in position to be engaged by the pins 46 and the links then supported by bracket 46^a in raised position, thus holding the angle 43 out of the path of 35 the angle 16. When the outer edge of the angle 43 is swung vertically about its pivots 44, the inner upturned flange of the angle moves through an arc and is thus guided into and out of its seat between the plates 21 40 and 22.

At its bottom edge, the car end is provided with two pairs of ears 50 (Fig. 2) that are 45 perforated for the reception of locking pins 51 which serve to retain holding levers 52 in locked position. The levers 52 are pivotally connected to an angle 53 that extends across the lower end of the car door and has its inner edge 53^a interlocked with the edge 23^a of the plate 23. The lever 52 is provided 50 with a nose portion 52^a that engages the bottom angle 15 of the door, when in closed position, thereby holding the outer end of the angle 53 in elevated position. The overlapping edges 23^a and 53^a serve as a seal. When 55 the latch 52 is swung outwardly, the outer edge of the angle 53 drops clear of the angle 15, to permit opening of the door. A guide plate 54 is secured to the inner face of the door to bring it to proper vertical position 60 when the door is being closed.

From the foregoing it will be seen that I provide a door that may be readily opened and wherein the edges are effectively sealed. 65 The door possesses a still further advantage in that pressure of lading against the inner

face thereof will not cause spreading of the joints between the vertical edges of the door and the car sides, by reason of the fact that the hinges and the latches cooperate as tie members to maintain the sides and the door 70 in proper relative position. The sealing plate 43 at the upper edge of the door and the angle 23 at the lower edge of the door, serve to hold the door against outward movement, as well as to seal the spaces at the 15 upper and lower edges.

I claim as my invention:

1. The combination with a door frame and a door movable in a direction transversely of its plane, of an angle member secured to the door at one edge thereof, a spring plate secured to the door frame, and a plate carried by said spring plate and normally overlapping the said angle member, the said angle member and the second-named plate being substantially co-extensive in length with the vertical edge of the door.

2. The combination with a door frame and a door movable in a direction transversely of its plane, of a plate secured to the door at one edge thereof, a spring plate secured to the door frame, a sealing plate carried by said spring plate, the sealing plate normally overlapping the first-named plate, and a camming member mounted in position to flex the spring plate outwardly to permit the other plates to clear one another, the said angle member and the sealing plate being substantially co-extensive in length with the vertical edge of the door.

3. The combination with a door frame and a door movable transversely thereof, of an angle at one side of the door frame and substantially co-extensive in length with the adjacent edge of the door, a plate secured to the door in position to abut against an inner surface of the said angle when the door is closed, a spring plate secured to the door frame and to the angle and arranged to yieldably hold said angle at an inner position and in overlapping relation to the plate when the door is closed, and means for holding said angle against movement relative to the said plate and for flexing said spring plate to move the angle out of said overlapping relation.

4. The combination with a door frame and a door, of an angle disposed along one edge of said door, a second angle carried by said frame, and means for yieldably supporting one of said angles in position to overlap the other angle, the said angles being substantially co-extensive in length with said edge of the door.

5. The combination with a door frame and a door, of an angle disposed along one edge of said door, a second angle carried by said frame, means for yieldably supporting one of said angles in position to overlap the other angle, and means associated with one

of said angles for varying the relative positions of the angles, the said angles being substantially co-extensive in length with said edge of the door.

5 6. The combination with a door frame and a door, of an angle disposed along one edge of said door, a second angle carried by said frame, and means for movably supporting one of said angles in position to overlap the 10 other angle, the said angles being substantially co-extensive in length with said edge of the door.

7. The combination with a door frame and a door pivotally supported at one of its 15 edges on said frame, of an angle bar secured to said frame adjacent to the pivotal support for the door, a sealing plate carried by said door and movable into and out of position behind one flange of the angle 20 when the door is swung on its pivot, and an angle plate at the opposite edge of said door and movable into and out of overlapping position with respect to said door edge, when the door is closed.

8. The combination with a door frame, of 25 a door having rearwardly bent portions at two opposite edges, arranged to engage outer surfaces of the door frame when the door is closed, to hold the frame against spreading, means carried by the door frame 30 for rigidly holding the door in closed position, and angle bars carried by the door frame in position to overlie the outer face of the door at said edges when the door is closed.

35 9. The combination with a door frame, of a door having rearwardly bent portions at two opposite edges, arranged to engage outer surfaces of the door frame when the door is closed, to hold the frame against spreading, 40 means for pivotally connecting one of said door edges to the frame, and an angle bar mounted on the frame and movable into overlapping engagement with the other door edge, to hold the door closed.

45 In testimony whereof I, the said ANDREW CHRISTIANSON, have hereunto set my hand.

ANDREW CHRISTIANSON.
